(57) **CLAIM**

The ornamental design for a shelving support bracket, as shown and described.

DESCRIPTION

FIG. 1 is three-dimensional view of my new design from the front left and right side of the shelving support bracket in accordance with the present invention. The circles on the surface of the shelving support bracket are indicating holes.

FIG. 2 is a top view thereof;

FIG. 3 is a bottom view thereof; and,

FIG. 4 is a side view thereof; all sides being identical.

The shelving support bracket is made of a polymer or metal that allows three or four pieces of shelving or structural material to be fastened together to form a 90 degree angle to each other, then at the same time, allowing the combination of boards or structural material to be fastened to a wall for which the following is a specification, reference being had to accompanying drawings, forming a part thereof.

1 Claim, 4 Drawing SheetsFIG 1

FIG 2

FIG 3
